United States Patent Office

Des. 194,634
Patented Feb. 19, 1963

194,634

BOTTLE OR SIMILAR ARTICLE

Joseph C. Smith, Los Angeles, and Martin J. Mann, La Habra, Calif., assignors to Purex Corporation, Ltd., Lakewood, Calif., a corporation of California

Filed July 9, 1962, Ser. No. 70,839

Term of patent 14 years

(Cl. D58—6)

FIG. 1.

FIG. 2.

FIG. 3.

FIG. 4.

FIG. 1 is a side elevational view of a bottle embodying our new design, the side of the bottle not shown being the same as the side shown;

FIG. 2 is a left side elevational view of FIG. 1;

FIG. 3 is a right side elevational view of FIG. 1; and

FIG. 4 is a top plan view of FIG. 1.

We claim:

The ornamental design for a bottle or similar article, substantially as shown and described.
